HOGSHEAD

William S. Luckett, New York, N. Y.

Application August 17, 1935, Serial No. 36,723

10 Claims. (Cl. 217—44)

My present invention relates to hogsheads or the like, especially adapted for use in storing, aging, and shipping leaf tobacco.

As is well known, leaf tobacco is cut and cured by the growers or farmers, after which it is graded and taken in a loose state to auction warehouses where it is sold to the manufacturers of tobacco products or to leaf tobacco dealers. The manufacturers of tobacco products, as well as the leaf tobacco dealers, take the tobacco to their plants where, after certain preliminary treatments, it is packed in hogsheads which are then stored in properly ventilated storage warehouses and allowed to remain in the hogsheads and storage warehouses for a considerable length of time, that is, generally from two to three years for aging purposes.

For a great many years it has been the general custom, and at the present time it is the general practice, to construct the hogsheads on the premises or adjacent the premises where the tobacco is to be stored for the aging purposes. In constructing the hogsheads a great quantity of staples and nails are used in securing the staves, hoops and heads of the hogsheads in place. Due to the fact that the tobacco sweats in the hogsheads at certain times, and also because of rough handling of the hogsheads, a great many of the staples and nails become loosened, and the hoops originally secured in place thereby fall off of the hogsheads.

After the tobacco has been properly aged the hogsheads with their contents are sent to the factories where the leaf tobacco is to be manufactured into the usual products. To gain access to the interior of the hogshead, as generally constructed, it is necessary to at least partly demolish them. The removal of the nails and staples, and splintering of the staves and heads results in causing foreign matter, such as the nails, staples and splinters of wood becoming admixed with the tobacco. This is objectionable because the manufactured products should not contain foreign matter, and the presence thereof in the tobacco during manufacturing processes often results in serious damage to the machinery. Very great care must be, and usually is, taken to remove even the most minute particles of metal and splintered wood from the tobacco prior to and during the manufacturing processes which requires not only the utmost vigilance on the part of those handling the tobacco, but also necessitates providing special equipment on many of the machines intended to remove the particles

of metal and other foreign matter from the tobacco.

With the foregoing in mind the principal general object of my present invention resides in the provision of a knock-down hogshead which may be assembled and disassembled with facility and in a very short period of time by one person, and which, when assembled, possesses great strength so that it will withstand all pressures, stresses, and forces created and encountered during the packing of the tobacco in the hogsheads, during aging and sweating of the tobacco in the hogshead, and during handling of the hogsheads, that is, when loading the hogsheads, storing them, unloading them, and shipping them.

While the foregoing general object of the present invention is similar to that of my co-pending application Ser. No. 16,677 filed April 16, 1935, I provide in the present invention for a unitary hogshead instead of a separable hogshead, and certain improvements with respect to the construction and mounting of the staves, binding of the staves, and construction of the heads as hereinafter pointed out in detail.

An important object of the present invention resides in the construction of the respective heads or ends of the hogsheads, one of which I will term the bottom head, which is preferably formed or stamped from a sheet of metal in the nature of a disc provided around its periphery with a stave receiving channel, and elements adapted to readily receive and hold in place certain of the staves. The other of the heads, which I will term the top, is preferably provided with an outside top hoop or binding band readily applicable around the ends of the staves regardless of discrepancies in the dimensions of the staves, the circumference of the hogshead, or any irregularities therein.

Another important object of the invention resides in the provision of a head so constructed as to resist the effects of forces or shocks which would split heads constructed and mounted in the usual manner.

Another important object of the invention resides in the provision of anchoring means for wire hoops applied at predetermined intervals around the hogshead and capable of definitely locating the hoops and maintaining them in definite locations throughout the entire aging period of the tobacco, and permitting reuse of the wire hoops after the hogshead has been emptied and disassembled.

The foregoing and other objects and advan-

- gates of the invention in its preferred form and several modifications will be pointed out in detail during the course of the following description of the accompanying drawings, in which
- 5 Fig. 1 is an elevation of a hogshead embodying a preferred form of my invention with parts broken away and partly in section;
- Fig. 2 is a perspective view of one of the attaching staves;
- 10 Fig. 3 is an enlarged fragmentary sectional view taken longitudinally through one of the attaching staves and the top head in assembled relation;
- Fig. 4 is an enlarged sectional view taken on the line 4—4 of Fig. 1 at the bottom of the hogshead;
- 15 Fig. 5 is a view taken on the line 5—5 of Fig. 3;
- Fig. 6 is a fragmentary view looking in the direction of the arrows on the line 6—6 of Fig. 4;
- 20 Fig. 7 is a perspective view of one of the wire hoop receiving and retaining plates;
- Fig. 8 is a perspective view of one of the plates used in connecting the plates Fig. 7 to 25 the hogshead;
- Fig. 9 is a top plan view of the hogshead shown in Fig. 1;
- Fig. 10 is a transverse central sectional view across the bottom of the hogshead shown in 30 Fig. 1;
- Fig. 11 is a perspective view of the binding hoop for the top of the staves of the hogshead shown in Fig. 1;
- 35 Fig. 12 is a view taken on the line 12—12 of Fig. 4;
- Fig. 13 is a view in elevation with parts broken away and partly in section of a hogshead embodying a modification of the invention;
- 40 Fig. 14 is a fragmentary sectional view on an enlarged scale of the fastening means for the bottom shown in Fig. 13;
- Fig. 15 is a view taken on the line 15—15 of Fig. 14;
- 45 Fig. 16 is a view similar to Fig. 14 showing the fastening means for the top of the hogshead shown in Fig. 13;
- Figs. 17 and 18 are perspective views of fastening plates used on certain of the staves in the embodiment shown in Fig. 13 to secure them to 50 the top and bottom heads respectively;
- Fig. 19 is a top plan view of a modification of the means for securing the binding band around the periphery of the head and affording adjustment of the band relative to the head;
- 55 Fig. 20 is an enlarged fragmentary sectional view similar to Fig. 3 showing a further modification of the invention;
- Fig. 21 is an enlarged fragmentary sectional view similar to Fig. 4 showing another modification of the invention in respect to the means for holding the bottom head in place;
- Fig. 22 is a view taken on the line 22—22 of Fig. 21 looking in the direction of the arrows;
- 60 Fig. 23 is a fragmentary enlarged side elevation of parts shown in Fig. 21;
- Fig. 24 is a top plan view of the connecting pin or cotter shown in Fig. 20 to hold the top head in place; and
- 70 Fig. 25 is an enlarged fragmentary view in elevation of one of the plates carried by the staves showing a modification and the means of detachably securing the ends of the wire hoops.
- 75 Referring to Fig. 1 the letters A designate the assembling staves, while the letters B designate

the intermediate staves, all of which are arranged in an annular group forming the wall of the hogshead between the upper head designated generally by the letter H and the lower head or bottom designated by H'. The staves 5 are preferably formed of either solid wood or laminated wood known as ply-wood. The wooden portion of the staves A is preferably of substantially the same width as the staves B, but slightly shorter.

10 Referring to Figs. 2 and 3 it will be noted that the tops of the staves A have secured thereto U-shaped plates 20 of slightly less width than the staves and having their bottom edges curved as designated by the numeral 21 to avoid 15 clearly defined or sharp straight edges across the staves, which straight edges, during handling of the staves and dropping them from a considerable height, might result in breaking the staves. However, the round bottoms of the U- 20 shaped plates avoids this tendency to breakage. The lower ends of the plates 20 overlap the ends of the staves A, and are secured thereto by rivets 22 or the like which pass through the front and back portions of the plates 20 as well 25 as through openings in the staves A. Thus the upper ends of the staves are re-enforced by the metal plates 20.

The U-shaped plates 20 have openings 23 provided by cutting and bending wings 24 from 30 the front and back portions or arms of the plates 20 and bending them inwardly in opposite directions across the space between the front and rear of the plate. The upper ends of the staves A abut the lower ends of the wings 24 and also 35 provide pockets to receive filler blocks 25 which are inserted in said pockets from the bottoms of the plates 20 before they are attached to the staves A by the rivets 22. Thus as shown in Fig. 3 the filler blocks 25, preferably of metal, 40 are definitely confined between the wings 24, the tops of the staves A and the tops 26 of the plates 20. The filler blocks 25 are also provided with screw threaded openings 27 alined with the openings 23 and said screw threaded openings 45 are definitely located due to the relative size of the fillers and the pockets provided by the wings 24, tops 26 of the plates 20, and tops of the staves A, certain of the filler blocks, as presently described have two screw threaded 50 openings.

Each of the staves A is also provided at its lower or bottom end with a plate 33, generally similar to the plates 20, and attached in the same manner by rivets 34 adjacent the preferably rounded edges 32 similar to edges 21. The plates 33 are also of U-shape and have openings 33 in their opposite arms. Intermediate the sides of each of the plates 33, and extending from the bottom 34 is a bayonet slot 35.

60 As many of the staves A, constructed substantially as above described, may be used as desired, and in the accompanying drawings, Figs. 1-11, I have shown provision for eight of the said staves, although six, four or any other number may be used. In other words, there is no limitation on the number of staves A having the attaching plates 20, 33 at their ends.

65 In the preferred form of the invention shown in Figs. 1-12 and being described, I also provide a stamped-up or cast metal bottom head H', including an annular base 37, which may be ribbed for additional strength, if desired, and having around its periphery a stave receiving groove or channel defined by an inner wall 38, 75

bottom wall 39, and upstanding outer wall 40. If desired, the outer wall 40 may be provided with a bead 41, and be also bent upon itself at its top as indicated at 42 for additional rigidity or strength.

The space between the walls 38 and 40 is such as to receive the plates 30 and the bottoms of the staves B. At regular intervals, corresponding to the number of staves A and plates 30 used, the walls 38 and 40 have portions 43 and 44 struck up therefrom into overlapping relation extending across the channel or groove between the walls 38 and 40 and adapted to fit into the bayonet slots 35 of the staves A. As previously mentioned, in the present case I have illustrated the use of eight staves A having plates 30 and eight bayonet slots 35, so that there would be eight of the overlapping portions 43 and 44 which when struck up provide openings 45 around the bottom of the hogshead.

To assemble the staves forming the wall of the hogshead, the staves A, that is, those having the plates 20 and 30 attached to the ends thereof, are first placed in position by inserting the plates 30 within the channel of the bottom head H' between the walls 38-40 with the overlapping ears or portions 43-44 alined with the longitudinal portions of the bayonet slots 35 on the plates 30, after which the staves A are given a lateral twist or movement to position the portions or ears 43-44 in the longitudinal ends 46 of the bayonet slots. The staves B, that is, plain wood staves, equal to the combined length of the staves A plus the plates 20 and 30 thereon are then inserted in the channel in the bottom head H' between the staves A. To complete the hogshead it is then only necessary to bind the tops of all of the staves, and to insert the top head H.

At this point I would explain that in connection with the storing and aging of tobacco, the hogshead thus far above described would preferably have inserted on its interior over the disc or bottom 37 a veneer or wooden disc 47, so that little or no metal would contact the tobacco. I would also point out that the integral or unitary structure of the metal base or bottom head H' greatly facilitates assembly of the hogshead and imparts thereto great strength sufficient to resist all strains, stresses and blows encountered during packing of the hogshead, handling thereof, and aging of the tobacco therein.

In completing the hogshead the first step, after positioning the respective staves in the manner just specified, is to bind their tops, and this, in the preferred form of the invention, is accomplished by providing an outer binding band shown in detail in Fig. 11 and designated generally by the numeral 49. This band is in the nature of a split metal ring, preferably though not necessarily, having adjacent its lower edge a strengthening bead 50 and on its top an inwardly extending flange 51. At the point designated by the numeral 52 the flange 51 is cut away so that the end 53 of the band is plain or straight to engage under the end of the flange 51 on the opposite end of the band, thus permitting a straight overlap at the ends of the band. At the center of the band there are provided two openings 54 and 55, and those of the staves A which are used at diametrically opposite points of the hogshead and band 49, that is, at the split end thereof and the center thereof, have provided in their plates 20 filler

blocks 25 each provided with a pair of screw threaded openings to align with the openings 54 and 55 and the openings at the split end of the band about to be described.

One end of the band 49, that is, the outside end which overlaps the inner cut away or notched end 53 is provided with a pair of openings 56 and 57 while the inner or overlapped end 53 is provided with an equally distance spaced pair of openings 58 and 59 adapted for alinement with the openings 56 and 57 when the band is drawn around the tops of the staves with the flange 51 disposed over the ends of the staves. To facilitate application of the band 49 to the ends of the staves, I provide also an opening 60 in the band, preferably adjacent the overlapped or notched end 53, so that a compressing tool may be inserted in the opening 60 and in the opening 56 to draw the openings 57 and 58 into alinement to receive a short screw 61 engaging into the filler in the stave A which is disposed at this particular point on the hogshead. Thus the band is held closed. Another short screw 62 is inserted through the opening 54 and into the proper opening in the filler in the stave A diametrically opposite. Preferably, the latter mentioned screw is inserted first through the opening 54 and tightened before the screw 61 is inserted and tightened. Thus the band 49 is centered on the tops of the staves, and due to the fact that I preferably provide elongated openings or slots 63 at definite intervals around the band 49, corresponding to the intervals at which the other staves A are arranged, the band may be applied with no difficulty and in a very short period of time, regardless of irregularities in the staves and the circumference of the upper end of the hogshead where staves B are encircled by band 49.

At the time when the staves have thus been secured at their tops and bottoms, I also preferably bind them intermediate their tops and bottoms circumferentially by wire hoops to prevent warping of the staves or breakage thereof or undesirable bulging when the hogshead is packed and handled. A preferred form of binding the hogshead with the wire hoops consists in applying to the outer surfaces of some or all of the staves as presently described, and at desired intervals, plates 65 shown in detail in Fig. 7, the length of the plates 65 being substantially the same as the width of the staves. Adjacent their ends the plates 65 are provided with openings 66, and are also crimped to provide bulges 67, provided with hoop receiving openings 68. To rivet or otherwise securely fasten the plates 65 to the wooden staves would ordinarily require the use of washers, and if desired, washers may be used on the opposite sides of the staves, but I prefer to provide elongated plates 69 shown in detail in Fig. 8 and adapted to extend substantially entirely across the staves and being of substantially the same dimensions as the plates 65. The plates 69 are provided adjacent their ends with openings 70 spaced apart the same distance as the openings 66 so that rivets or the like 70 may be secured through the plates 65, the staves, and the plates 69.

I find that the foregoing arrangement of the plates 65 and 69 extending substantially across the staves imparts a re-enforcement thereto against longitudinal splitting, and while I have shown in Fig. 1 the plates 65 distributed at

- irregular intervals with at least one attached to each of the staves A and B in the manner above described, I wish it to be understood that I may arrange the plates 65 so as to have one or more 5 on one stave and a corresponding number on a diametrically opposite stave, or two on diametrically opposite staves in one direction and two on diametrically opposite staves in another direction, etc.
- 10 While any type of wire possessing sufficient tensile strength may be used to form the intermediate hoops by threading the wire through openings 68 in plates 65 and twisting the ends together, I preferably provide ready cut and 15 formed lengths of wire to form the hoops designated by the numeral 71. These predetermined lengths of wire have at one end thereof loops 72 formed by bending the wire and twisting it upon itself in any suitable manner. The other ends 20 of the wires are straight in their original form. To apply the hoops 71 the wire is inserted through the aligned openings 68 in the respective plates 65 at the predetermined intervals 25 at which the plates are arranged longitudinally of the hogshead with the loops 72 adjacent one of the plates 65. When the wires have been entirely passed around the hogshead and through the openings 68 in the aligned crimps of the respective plates, the free ends of the wires 30 are passed through the loops 72 and bent back upon themselves and inserted again in reverse direction through the last of the pair of openings 68 with a wedging action after pulling them taut to hold the hogshead against excessive expansion between its ends. Of course if desired, the free end of the wires may be twisted upon themselves after being passed through the loops 72 and tightened, or may be bent back after passing through the last of the openings 35 40 in the final plate 65. The wire hoops constructed in accordance with my invention are obviously reusable and retain their original established positions on the hogsheads due to the fixed positions of the attaching plates 65 45 which maintain the wires in place.
- The next step is to fill and close the hogsheads. In the case of tobacco, it is dumped in and pressed down under considerable pressure, after which the top heads H are inserted 50 and secured in place.
- In the present preferred form of the invention, as well as in the modification thereof, although not essential, I construct the top heads H of a disc of wood constructed either of separate 55 boards or of a disc of ply-wood and designated by the numeral 74. I encircle this disc of wood marginally by a channel shaped annular metal band 75 of greater diameter than the disc 74. As shown in Fig. 9 the ends of the channel shaped band overlap as at 76 and are secured 60 together by rivets 77 which extend therethrough. Thus the wooden disc 74 may shift laterally within the band 75 so that if the hogshead so falls that a severe blow is encountered at the top head adjacent the edge thereof, the metal band 65 75 will withstand the blow and the wooden disc 74 may shift within the band 75 to avoid splitting the wooden disc.
- After the hogshead has been completely filled 70 under pressure the upper head H comprising the parts 74, 75 is placed on top of the contents and pressed down until screws 78 having a portion 79 of their shanks screw threaded and their outer ends 80 unthreaded and elongated may be inserted through the openings 63 in the band 49

and into the openings 27 in the filler blocks 25, to hold the head firmly but removably locked on the hogshead. It will be noted by reference to Fig. 9 that two of the screws 78 are also inserted through the openings 55 and 56—59 of the band 5 adjacent the shorter screws.

It should be apparent from the foregoing that hogsheads embodying the features just described may be readily assembled to receive the tobacco, and will withstand all of the stresses and forces 10 encountered during the aging process, handling and shipment, and after the aging process is completed, may be readily disassembled and stored in flat condition, occupying relatively small storage space. When it is again time to 15 assemble the hogsheads, all of the parts may be reused. Furthermore during the assembly and disassembly it is not necessary to break any of the parts, nor to forcibly remove individual fastening elements, which in the case of the 20 usual hogsheads become admixed with the tobacco.

While the foregoing disclosure embodies a preferred form of my invention I have also shown modifications, and in Fig. 13 have illustrated an 25 assembled hogshead embodying the general principles of the preferred form, but varying therefrom in certain details about to be described.

Referring to Fig. 13, the letters A' and B' 30 designate staves corresponding to staves A and B in the preferred embodiment of the invention of Figs. 1-12, that is, the attaching staves and the intermediate or filler staves. The numeral 82 designates the top head corresponding to that of the preferred form of the invention, that is, 35 having a wooden disc enclosed within a channel binding strip permitting shifting movement of the wooden disc as previously described and for the same purpose.

Instead of providing U-shaped attaching plates 40 20 and 39 of Figs. 1-4 on the attaching staves, I may provide as shown in Figs. 13-18, on the tops of the staves A', plates designated generally by the numeral 83 having solid top portions 84 and bifurcated bottoms 85 provided with a 45 channel 86 to receive the top ends of the staves. Some of the plates 83 are preferably provided with two openings 87, one of which receives the short screws 62 which secure the top binding band 88 corresponding to the band 49 in position on the top of the hogshead, and others of which may be provided with single central openings 87 to receive the elongated screws 89 corresponding to the screws 61 which hold the head on the hogshead. The lower or bifurcated ends 55 of the plates 83 are provided with openings 90 to receive screws 91 extending through the staves located in the channels 86 and securing the plates to the ends of the staves. The band 88 is also provided with slots 92 which receive screws 60 89 in the same manner that the slots 63 in the band 49 receive the screws 61.

Another difference in the embodiment of the invention shown in Figs. 13-18 from that shown in Figs. 1-12 resides in the provision of plates 65 93 on the lower ends of the staves A'. The plates 93 are generally similar to the plates 83, but reversed in that the upper ends of the plates 93 are bifurcated to provide the stave receiving channels 94 between the arms 95 which are provided with the openings 96 to receive screws 97 extending through the lower ends of the staves and securing the plates 93 thereto. The lower ends of the plates 93 are provided with bayonet slots 98.

Also in the modification of the invention, and as shown best in Figs. 13 and 14, the bottom of the hogshead has an encircling outside band 99 which may be provided adjacent its top with a bead 100 and folded upon itself at 101 above the bead to impart additional strength to the band. The band 99 also has an inwardly extending flange 102. Another or inner band 103 of substantially Z-shape has a lower flange 104 on which the flange 102 rests. The overlapping ends or flanges 102 and 104 of the bands 99 and 103 provide a channel or groove 105 to receive the staves. The band 99 carries or holds in place pins which support the bottom head 106, which is encircled around its periphery or marginal portions by an L-shaped metal band 107. The pins which hold the bottom head 106 in place have elongated shanks 108 extending from an angular or square shoulder 109, at the outer ends of which are reduced ends 110 which may be peened over or riveted to form heads 111 locking the pins to the band 99. Of course the inner band 103 has openings 112 to receive the shanks 108 of the pins and the outer band 99 has openings 113 to receive the reduced ends 110.

In assembling the plates 99, 103, head 106 and locking pins, the pins are secured to the band 99. The head 106 is positioned against the top flange 114 of the Z-shaped plate 103 and then the outer band 99 is placed around the inner band 103 with the ends or flanges 102 and 104 overlapping and with the shanks 108 of the pins carried by the bands 99 extending through the openings 112 of the band 103 beneath the head 106. This provides the channel 105 between plates 99 and 103 to receive the staves B' and the lower ends of the plates 93 on staves A'. In other words, instead of providing the integrally cast or stamped metal bottom having the stave receiving channel as in Figs. 1-12, I assemble the parts 99, 103 and 106 with the locking pins to receive the staves in the channel 105. Of course the shoulders 109 of the pins are disposed in such channel so that when the plates 93 on the staves A' are inserted, the said shoulders will be received in the bayonet slots of the plates 93 and upon lateral movement of the staves A', the same will be removably locked to the bottom head, after which the staves B' may be inserted between the staves A' in the same manner as explained in connection with the staves B and staves A of Figs. 1-12.

I would also call attention to the fact that the shoulders 116 on the plates 93, and 116' on the plates 83, are engaged by the respective heads, thus cooperating in holding the heads in place. Obviously the manner of assembly is the same as explained in connection with Figs 1-12, that is, the lower ends of the staves are first positioned in the channel 105 and then the upper band 88 is applied and secured in place by the short screws, following which the intermediate binding hoops 117 corresponding to the hoops 71 are bound around the hogshead.

Whereas in the embodiment of the invention shown and described in connection with Figs. 1-12, I show and describe separate plates 65 secured to certain or all of the staves to hold the hoops in place, in the modification being described I provide, preferably on the staves A', elongated metal strips 118 having at predetermined intervals bends or crimps 119 providing channels 120 through which the hoops are disposed. The strips 118 may be attached to the

staves by rivets or screws 121 with washers or locking plates 122 arranged on the opposite sides of the staves. The hoops 117 are preferably constructed in the manner described in connection with the hoops 71, but may be held in place by separate tubular locking devices 123 through which the wire extends in opposite directions and with the free end of the wire bent over the locking device as indicated at 124.

In Fig. 19 I have shown a modification of the invention applicable to either form above described in connection with the re-enforcement or binding of the upper heads. In Fig. 19 the ends of the channel shaped or binding member 75' corresponding to binding member 75 are shown connected by an adjustable link 126 which is fixedly secured at one end as indicated at 127 by rivets or the like to one end of the binding band 75'. The other end of the link is provided with a slot 128, and the other end of the band 75' has a stop pin 129 located in the slot 128. The band 75' also carries a screw 130 which receives a washer 131 and nut 132 to hold the ends of the band 75' in properly spaced relation determining the desired circumference and permitting the lateral shifting of the wooden disc within the band 75'.

Referring to Fig. 20 there is shown a further modification of the invention in respect to the means for connecting or associating the locking plates on or with the attaching staves A', similar to the staves A, as well as a modification in the means for holding the top head H', similar to the head H, in closed position after the hogshead has been packed. I have previously described the preferred form of construction of the top head, and having shown the same form in Fig. 20 deem no further detailed description thereof necessary.

Whereas in Fig. 18 I show an attaching plate 83 having an upper end 84 formed integrally with a bifurcated lower portion providing arms 85 and 86 to embrace the upper ends of the attaching staves, in Fig. 20 I have shown the modification consisting in the provision of a plate 135, of substantially the same width as the staves A', adapted to be arranged on the top of said staves and secured thereto by metal straps 136, 136' extending along the inner and outer faces of the staves A' and overlapping the lower ends of the plates 135. Rivets 137 secure the straps 136, 136' to the plates 135, and rivets 138 secure straps 136, 136' to staves A'. Thus the plates 135 are connected to the ends of the attaching staves A'. An encircling band 49', corresponding to band 49 of Fig. 1 and having the bead 50' corresponding to bead 50, is arranged around the top of the hogshead and secured in place in the same manner as described in connection with the band 49. On each plate 135 I provide a projection or bead 139 adapted to receive the bead 50'; and on the opposite face of the plates 135 I provide projections 140 which act as stops to downward movement of the head H'. Of course the provision of the projections or beads 139 and 140 is optional, but I find that they impart additional strength to the hogshead and facilitate assembly of the parts.

The band 49' and the plate 135' are provided with registering openings 141 similar to the openings 27, that is, located similarly, but the openings 141 are not screw threaded, and are angular to receive the split pins or cotters designated generally by the numeral 150 in Fig. 20 and shown in detail in Fig. 24.

Referring to Fig. 24 the numeral 151 designates the head of the split pin or cotter, which head is of greater circumference than the openings 141. The said pin or cotter 150 is provided 5 with a neck 152, which is rectangular or polygonal in cross section to correspond to the cross sectional shape of the opening 141, and of a length substantially the same as that of openings 141. The head 151 of the pin or cotter 150, 10 when the pin or cotter is inserted through the alined openings 141, of course is located on the exterior or outside of the attaching staves or the plates 135 forming a part thereof. The neck 152 terminates at its inner end at tapered 15 shoulders 153, which are spaced apart further in normal condition than the diameter or cross sectional area of the openings 141. Beyond the shoulders 153 the coppers 150 are provided with elongated shanks 154 divided by a cutaway portion 20 or channel 155 defining the space between the shanks 154 as well as the opposite portions of the neck 152. The coppers or split pins 150 are formed of resilient metal so that the shanks 154 are normally urged apart so that shoulders 25 153 will hold the pins in openings 141 for abutment by the top head. When the hogshead embodying or constructed in accordance with any of the features previously described in connection with the bottom closure has been fully 30 packed, it may be closed by pressing the head H' down against the lateral projections or beads 140 on the plates 135 and then driving the coppers or split pins 150 through the openings 141. It will be obvious that when the shanks 154 have 35 completely passed through the openings 141 that the shoulders 153 will expand thus removably locking and holding the heads H' in closed position on the hogshead.

Due to the resilience and construction of the 40 coppers or split pins 150, to open the hogshead it is simply necessary to strike the inner ends of the shanks 154 with sufficient force to cause the beveled surfaces of the shoulders 153 to ride through the openings 141, thus contracting the 45 pins or coppers 150 so that complete removal may be made with facility.

In Figs. 21-23 I have shown a modification 50 of the invention in respect to the means for holding the lower head or bottom of the hogshead in place. Whereas in the embodiment of the invention shown in Fig. 4, I provide overlapping portions 43 and 44 on the encircling bands to engage in the bayonet slot 45 on the plates 36; and in Fig. 14 show locking members 55 carried by the band 99 and having portions 109 to engage in the bayonet slots, and shanks 108 disposed beneath the bottom or lower head; in the form of the invention shown in Figs. 21-23 I provide a modified form of locking device for 60 the lower head or bottom. Metal straps 157, 157' similar to straps 136, 136' of Fig. 20 are secured to the lower ends of the attaching staves as by means of rivets 158. The lower ends of the straps 157, 157' project beyond the 65 lower ends of the attaching staves and provide pockets to receive the upper ends of plates 159 through which and straps 157, 157' are rivets 160 securing the said plates 159 to the lower ends of the attaching staves A'.

70 A band or hoop of channel shape in cross section, and having an outer wall 161 and an inner wall 162 joined by the bottom 163, is provided to receive the lower ends of the staves and the locking plates 159 on the attaching staves. The said hoop or band is provided with 75

a lateral flange 164 extending inwardly from the upper end of the inner wall 162. The lower head or bottom 165 is bound around its margin by a band or hoop 166. The head 165 is adapted to rest on the flange 164 when the hogshead 5 is assembled.

To firmly hold the lower head or bottom 165 in place, in the embodiment of the invention shown in Figs. 21-23, I provide plates designated generally by the numeral 167 having a portion or neck 168 to fit in the bayonet slots 169 of the plates 159. The outer ends of the plates 167 are peened over against the outer wall 161 of the bottom encircling band to provide heads 170 securing the plates 167 to said band. The 15 other ends of the plates 167 are relatively broad and flat and provided with grooves 171 which receive the flanges 164 of the encircling band when the parts are assembled. Alined openings are formed through the tops of the bands 20 166 through the heads 165, flanges 164 and plates 167 to receive rivets or equivalent fastening elements 172 to hold said parts together and securing the bottom or lower head of the hogshead firmly in place. If desired, the outer 25 ends 173 of the plates 167 may be provided with openings to receive rivets as shown in dot and dash lines in Fig. 21 and designated by the numeral 174 to further secure the plates 167 to the bottoms or lower heads 165.

In Fig. 25 I have shown still a further modification, especially relating to the manner of securing the intermediate or binding wire hoops 71' around the hogshead. It will be understood that the construction of the hoops 71' is preferably the same as the hoops 71, and the modification of Fig. 25 resides in the manner of attaching or securing the free ends of the hoops. In other words, the hoops 71' have at one end loops 72' similar to loops 72, and plates 65' are 40 identical with plates 65 of Fig. 7, and may be attached to certain of the staves as desired. Also the plates 65' have the channels 61 extending transversely across the plates, and openings 68 thru said channels as shown in Fig. 7. 45 Under the embodiment of the invention shown in Fig. 25 after the wires or hoops 71' have been passed around the hogshead and through the openings 68 of the plates 65', the free end of the wire or hoops is passed through loop 72' and is then bent back as indicated at 175 and 50 through the channel or groove 67 as indicated at 176, and then bent over the plate 65' parallel with the groove 67 as indicated at 177. This manner of tying or attaching the hoops 71' is 55 accomplished with facility and affords a very firm attachment to removably hold the hoops around the hogshead.

I wish it to be understood that the several 60 modifications of the invention above described may be freely interchanged, that is, the different means of attaching the tops may be freely interchanged with means for attaching the bottoms, and the several means for securing the intermediate wire hoops around the hogshead 65 may be used with either or any of the means for attaching the tops and bottoms to the staves. For instance, the construction of either Fig. 3 or Fig. 20 may be used in connection with the construction of either Figs. 4, 15 or 21. I deem 70 it unnecessary to make any further mention of the interchangeability or selective use of the different embodiments of the invention in constructing hogsheads embodying the features and advantages above pointed out.

What I claim is:

1. A knockdown hogshead including top and bottom heads and a plurality of staves arranged in an annular group therebetween, at least one 5 of said heads having an annular channel to receive the staves at one end thereof, cooperating elements on certain of said staves and in said channel engageable upon longitudinal and lateral movements of said certain of the staves relative 10 to said one head to detachably secure said certain of the staves to said one head at predetermined intervals, the other of said staves being disposed intermediate said certain staves and located in said channel at one end, means to bind 15 the other ends of the staves, and means removably inserted through certain of the staves and engageable with the top of the other head to detachably secure the other head in place closing the other end of the hogshead.
2. A knockdown hogshead including top and bottom heads and a plurality of staves arranged in an annular group therebetween, at least one 20 of said heads having an annular channel to receive the staves at one end thereof, cooperating elements on certain of said staves and in said channel engageable upon longitudinal and lateral movements of said certain of the staves relative 25 to said one head to detachably secure said certain of the staves to said one head at predetermined intervals, the other of said staves being disposed between said certain staves and located in said channel at one end, a band encircling the 30 other ends of the staves, and means on said certain of the staves adapted to cooperate with said encircling band to hold said encircling band in position around said staves covering the upper 35 ends thereof and to hold the other head in closed position.
3. A knockdown hogshead including top and bottom heads and a plurality of staves arranged 40 in an annular group therebetween, at least one of said heads comprising a metal disc having a marginal channel formed integrally therewith to receive the staves at one end thereof, cooperating elements on certain of said staves and in 45 said channel engageable upon longitudinal and lateral movements of said certain of the staves relative to said one head to detachably secure said certain of the staves to said one head at predetermined intervals, the other of said staves 50 being disposed intermediate said certain staves and located in said channel at one end, means to bind the other ends of the staves, and means associated with the other ends of certain of the staves to detachably secure the other head in 55 place closing the other end of the hogshead.
4. A knockdown hogshead including top and bottom heads and a plurality of staves arranged in an annular group therebetween, at least one 60 of said heads comprising a metal disc having a marginal channel formed integrally therewith to receive the staves at one end thereof, cooperating elements on certain of said staves and in said channel engageable upon longitudinal and lateral movements of said certain of the staves 65 relative to said one head to detachably secure said certain of the staves to said one head at predetermined intervals, the other of said staves being disposed intermediate said certain staves and located in said channel at one end, means 70 to bind the other ends of the staves, and means cooperating with said binding means and said certain of the staves to detachably hold the other head in place closing the other end of the hogshead.
5. A knockdown hogshead including top and 75 bottom heads and a plurality of staves arranged in an annular group therebetween, at least one of said heads having an annular channel to receive the staves at one end thereof, cooperating elements on certain of said staves and in said channel engageable upon longitudinal and lateral movements of said certain of the staves relative to said one head to detachably secure said certain of the staves to said one head at predetermined intervals, the other of said staves being disposed intermediate said certain staves and located in said channel at one end, means to bind the other ends of the staves, and means to detachably secure the other head in place closing the other end of the hogshead, and detachable binding hoops encircling said staves intermediate said heads.
6. A knockdown hogshead including top and bottom heads and a plurality of staves arranged in an annular group therebetween, at least one 20 of said heads having an annular channel to receive the staves at one end thereof, cooperating elements on certain of said staves and in said channel engageable upon longitudinal and lateral movements of said certain of the staves relative 25 to said one head to detachably secure said certain of the staves to said one head at predetermined intervals, the other of said staves being disposed between said certain staves and located in said channel at one end, a band encircling the 30 other ends of the staves, and means on said certain of the staves adapted to cooperate with said encircling band to hold said encircling band in position around said staves covering the upper 35 ends thereof and to hold the other head in closed position.
7. A knockdown hogshead including top and bottom heads and a plurality of staves arranged in an annular group therebetween, at least one 40 of said heads having an annular channel to receive the staves at one end thereof, cooperating elements on the ends of certain of said staves and in said channel engageable upon longitudinal and lateral movements of said certain of the staves relative to said one head to detachably secure said certain of the staves to said one head at predetermined intervals, the other of said staves being disposed between said certain staves and located in said channel at one 45 end, a band encircling the other ends of the 50 staves, and means on the other ends of said certain of the staves adapted to receive removable fastening elements to cooperate with said encircling band to hold said encircling band in position around said staves covering the upper 55 ends thereof.
8. A knockdown hogshead including top and bottom heads and a plurality of staves arranged in an annular group therebetween, at least one 60 of said heads having an annular channel to receive the staves at one end thereof, cooperating elements on the ends of certain of said staves and in said channel engageable upon longitudinal and lateral movements of said certain of the staves relative to said one head to detachably secure said certain of the staves to said one head at predetermined intervals, the other of said staves being disposed between said certain staves and located in said channel at one 65 end, a band encircling the other ends of the 70 staves, and means on the other ends of said certain of the staves adapted to receive removable fastening elements to cooperate with said encircling band to hold said encircling band in position around said staves covering the upper 75 ends thereof.

ends thereof, and means engageable through said encircling band and said elements on certain of said staves to detachably hold the other head in place closing the other end of the 5 hogshead.

9. In a hogshead of the character described, attaching staves for the opposite heads of the hogshead comprising elongated boards having on opposite ends thereof metal plates embracing 10 the ends of the staves, reenforcing said ends and provided with means adapted to receive removable fastening elements to secure said staves in place, and plates secured across said staves at predetermined intervals intermediate the ends

of the staves and provided with hoop receiving and retaining elements.

10. A knockdown hogshead of the character described including a plurality of staves arranged in an annular group and bound at their opposite ends by detachable fastening bands, a removable head closing one end of the hogshead and composed of a disc of wood encircled by a re-enforcing metal band of channel shape in cross-section and of greater diameter than 10 the wooden disc whereby said wooden disc may shift within said channel shaped band for the purpose described. 5

WILLIAM S. LUCKETT.
